2 SHEETS—SHEET 2.

UNITED STATES PATENT OFFICE.

SYLVESTER V. FERGUSON, OF POLSON, MONTANA.

PUMP-OPERATING MECHANISM.

1,160,270.

Specification of Letters Patent. Patented Nov. 16, 1915.

Application filed September 16, 1914. Serial No. 862,060.

To all whom it may concern:

Be it known that I, SYLVESTER V. FERGUSON, a citizen of the United States, residing at Polson, in the county of Flathead and 5 State of Montana, have invented certain new and useful Improvements in Pump-Operating Mechanism, of which the following is a specification.

This invention relates to a pump operating mechanism and the principal object of 10 the invention is to provide an apparatus of the character described which is so constructed that a pump of the reciprocating type may be very easily operated, thus making it easy to operate the pump and doing away with the excessive labor necessary 15 when it is desired to fill a reservoir tank or to pump a great deal of water or for any other purpose.

Another object of the invention is to so 20 construct the device that it may be connected with pumps already in use.

Another object of the invention is to provide 25 an apparatus which will be comparatively simple in construction and which will operate very efficiently.

This invention is illustrated in the accompanying drawings, wherein—

Figure 1 is a front elevation of the improved 30 pump operating mechanism shown applied to a pump; Fig. 2 is a sectional view taken along the line 2—2 of Fig. 1; Fig. 3 is a top plan view of the pump operating mechanism; Fig. 4 is a side elevation of the 35 pump operating mechanism; Fig. 5 is a section taken along the line 5—5 of Fig. 3; Fig. 6 is a fragmentary view in elevation showing a modified form of the pump operating mechanism.

The frame of this pump operating mechanism 40 comprises the standards 10 which have their upper ends connected by the cross bar 11 and which are connected with the side supporting bars 12 and 13. The opposite 45 ends of the side bars 12 and 13 are connected with the transversely extending supporting bar or plate 14 which carries a substantially V-shaped bracket 15. One end of the bracket 15 is secured to the plate 14 and the 50 bracket then extends away from the plate for a short distance as shown in Fig. 3 and is carried upwardly in spaced relation to the plate with its opposite end forming a bearing for the driven shaft 16. This bracket 55 also forms a bearing for the shaft 17 the opposite end of which is mounted in the

bearing 18 carried by the plate 14. Upon the shafts 16 and 18 there has been provided gears 19 and 20 one of which is a great deal smaller than the other. If it is desired to 60 operate this pump operating mechanism by means of a belt passing around the pulley wheel 21 the large gear 19 will be placed upon the shaft 16 and the small gear placed upon the shaft 17 but if it is desired to operate 65 this mechanism by means of a handle 22, the large gear will be placed upon the shaft 17 and the small gear upon the shaft 16. This second arrangement is shown in Fig. 6. 70

The driven shaft 16 extends through the bearing blocks 23 and 24 which are connected by the bar 25 and carries a worm 26 which meshes with the teeth of the gear or pinion 27 mounted upon the crank shaft 28. 75 This crank shaft 28 carries a roller 29 which is mounted in the longitudinally extending slot 30 of the arm 31. In order to pivotally mount the arm 31 there is provided links or standards 32 which are mounted upon the 80 bolt 33 passing through a selected opening in the bar 33 and have their upper ends connected by the bolt 34 which passes through a selected opening formed in the arm 31 as shown in Fig. 2. This arm 31 85 carries plates or brackets 35 which are pivotally connected with the pump shaft 36 by means of the pivot bolt or rivet 37. When this mechanism is in operation, the apparatus is assembled and mounted as shown in 90 Fig. 1 with the supporting brackets 38 clamped to the upper end of the pump 39 by means of the bolts 40. The shaft 17 is then rotated either by means of the crank handle 22 or by means of a suitable belt 95 passing around the pulley wheel 21. Rotary motion is transmitted from the shaft 17 to the shaft 16 through the medium of the gears 19 and 20, thus causing the shaft 16 to rotate and transmit rotary motion to the 100 crank shaft 28 through the medium of the worm 26 and gear 27. As the crank shaft 28 rotates, the arm 31 will oscillate vertically, thus reciprocating the pump rod 36 and causing the water to be pumped out of 105 the well. This water can flow out through the spout 41 or the spout can be closed by means of the valve 42 and the water conveyed to a suitable receptacle by a conduit pipe connected with the pump at any convenient point. This mechanism is therefore 110 so constructed that it may be easily

applied to a pump which is already in use, it only being necessary to erect the framework and connect the brackets 38 with the pump 39 and the arm 31 with the pump shaft 36. It will also be noted that this device can easily be transformed from a hand-operating device as shown in Fig. 6 to a power operating device as shown in Fig. 4. It will of course be obvious that the opposite is also possible, that is to say, that it may be transformed from a power operating mechanism to a hand-operating mechanism as shown in Fig. 6. This is done by transposing the gears 19 and 20 and removing the handle 22 or pulley wheel 21 and putting the proper one in place. It should be noted that by having the arm and supporting bar provided with a plurality of sets of openings the links or standards can be adjusted thus regulating the length of stroke given the arm as the crank rotates. It should also be noted that by having the arm mounted as shown it will receive a relatively rapid movement when moving downwardly and will then move upwardly with a relatively slow movement, thus causing the pump to work smoothly.

What is claimed is:—

1. A pump including a pump rod, brackets carried by said pump, standards, supporting bars connected with said standards and brackets, a plate carried by said supporting bars, a bracket carried by said plate and provided with bearings, bearing blocks carried by one of said supporting bars, a bracing bar connected with said bearing blocks and plate, a driven shaft rotatably supported by said bearing blocks, plate and bracket, a driving shaft rotatably supported by said plate and bracket, means for transmitting rotary motion from said driving shaft to said driven shaft, a crank shaft rotatably carried by said supporting bars, means for transmitting rotary motion from said driven shaft to said crank shaft, an arm pivotally connected with said supporting bars and provided with a slot through which said crank shaft passes to oscillate said arm as said crank shaft rotates, and means pivotally connecting said arm with the pump rod of said pump to cause the pump rod to reciprocate vertically when said arm is in motion.

2. An operating mechanism of the character described comprising a frame, a bearing bracket carried by said frame, a drive shaft rotatably mounted between said frame and said bearing bracket, a driven shaft rotatably carried by said frame and having its outer end portions supported by said bearing bracket, means for transmitting rotary motion from said drive shaft to said driven shaft, a crank shaft rotatably carried by said frame, an actuating arm pivotally connected with said frame and provided with a longitudinally extending slot through which said crank shaft passes, and means for transmitting rotary motion from said driven shaft to said crank shaft.

3. An operating mechanism of the character described comprising a frame including side bars, a supporting plate carried by said side bars, a bearing bracket carried by said supporting plate, a drive shaft rotatably mounted between said supporting plate and bearing bracket, a driven shaft rotatably carried by said frame and supporting plate and having its outer end portion supported by the bearing bracket, means for transmitting rotary motion from said drive shaft to said driven shaft, a crank shaft rotatably connected with said side bars, an actuating arm pivotally connected with said side bars and provided with a longitudinally extending slot through which said crank shaft passes, and means for transmitting rotary motion from said driven shaft to said crank shaft.

4. An operating mechanism of the character described comprising a frame, an actuating arm, supporting links for one end of said actuating arm adjustably connected with said frame and arm to permit of pivotal movement of said arm, said links being longitudinally adjustable on said frame and arm to regulate the swinging movement of said arm, a crank shaft engaging the free end portion of said arm to oscillate said arm as said crank shaft is rotated, and means for rotating said crank shaft.

In testimony whereof I affix my signature in presence of two witnesses.

SYLVESTER V. FERGUSON.
